[57] **CLAIM**

The ornamental design for the boot protector, as shown and described.

DESCRIPTION

FIG. 1 is a front elevational view of the boot protector showing my new design;

FIG. 2 is a rear elevational view thereof;

FIG. 3 is a side elevational view thereof;

FIG. 4 is a top plan view thereof;

FIG. 5 is a bottom plan view thereof; and,

FIG. 6 is a perspective view showing a use thereof, the broken line showing of a boot for illustrative purposes only and forming no part of the claimed design.
